UNITED STATES PATENT OFFICE.

HARRY M. SCIPLE, OF SELIN'S GROVE, PENNSYLVANIA, ASSIGNOR TO HIMSELF AND HARRY U. KISTNER, OF SAME PLACE.

PORTABLE STEAM-ENGINE.

SPECIFICATION forming part of Letters Patent No. 224,481, dated February 10, 1880.

Application filed July 11, 1879.

To all whom it may concern:

Be it known that I, HARRY M. SCIPLE, of Selin's Grove, in the county of Snyder and State of Pennsylvania, have invented a new and Improved Portable Steam-Engine, of which the following is a specification.

The object of my invention is to furnish a portable steam-engine combining the features of lightness, durability, and cheapness to obtain the required strength with the least material and least labor in fitting.

The invention consists in a vertical steam-engine having the base, column, pedestal, cylinder, and steam-chest cast in one piece and fitted with the cylinder-head and cross-head guides, that are cast in one piece, whereby the required strength is obtained and there is but a single joint to be fitted; also, in the construction and manner of applying the connecting-rod, and in a novel construction of the cross-head guides and bearings, all of which features I will describe more particularly in connection with the accompanying drawings, wherein—

25 Figure 1 is a sectional elevation of the improved engine. Fig. 2 is a section horizontally through the cross-head guides on line xx of Fig. 1. Fig. 3 is a section through the cross-head on line yy of Fig. 2. Fig. 4 is an end view of the piston-head with the plate removed. Fig. 5 is a cross-section of the head on line zz of Fig. 4.

Similar letters of reference indicate corresponding parts.

35 The base a , column b , pedestal c , cylinder d , and steam-chest e are all cast in one piece in the form as shown.

The head f of the cylinder is cast with the vertical guides g of the cross-head h , which guides are united at the top by an arch.

40 By this construction the casting is done and the engine can be set up and fitted with less labor than is required when the parts are made separate.

45 The connecting-rod i is made in one piece, of malleable iron or steel, in the form of a yoke. The two upper ends are connected rigidly by nuts to the ends of a vibrating cross-bar, k , that is held in an adjustable bearing, l , in the center of cross-head h , and the lower end of the rod i is connected with the crank of the main shaft u beneath the cylinder d .

50 By this construction there is less friction than when the bearing is at each end of a

cross-beam, and the application of the power is directly in line with the piston.

The guides g of the cross-head are each formed with a V-shaped groove, and instead of the common slide I make use of elastic-faced rollers m , made of steel covered with 60 rubber, and held in slots in the cross-head by steel pins, on which they turn. These rollers m are of such diameter that they make one revolution at each stroke, and by their use there is but a small amount of friction. 65

The construction shown gives a connecting-rod longer than usual in proportion to the height of the engine, thereby reducing the side strain and friction on the guides and rollers of the cross-head. 70

The piston-head (shown separately in Figs. 4 and 5) consists of plates or disks n , connected together by screws entering the posts o on one plate, and carrying between them the outer expandable packing-rings, p , inner ring-segments, q , and expansion-wedges r . These wedges r wedge between the segments q and posts o , and are retained in place by radial spring-arms s , that project from the central hub, and are set up by screws t . 75

The above-described construction furnishes an engine durable in all its parts, comparatively light, and inexpensive. 80

By casting the pedestal, cylinder, and steam-chest in one piece there is a saving in bolts 85 and the labor of fitting joints, and the structure is very firm.

The construction described is especially adapted to a vertical engine, and the engine, by reason of its lightness and compactness, 90 can be used to great advantage on steamboats.

Having thus described my invention, what I claim as new, and desire to secure by Letters Patent, is—

1. In a vertical engine, the base a , column b , pedestal c , cylinder d , and steam-chest e , made in one casting, combined with the head f , cast with the guides g and attached upon the cylinder d , substantially as and for the purposes set forth. 95

2. The elastic rollers m , in combination with the cross-head h and V-shaped guides g , substantially as and for the purposes described. 100

HARRY M. SCIPLE.
